UNITED STATES PATENT OFFICE.

JAMES EDWARD McCALL, OF MONTGOMERY, ALABAMA.

CHIMNEY-CAP.

1,068,257.

Specification of Letters Patent.

Patented July 22, 1913.

Application filed October 12, 1912. Serial No. 725,428.

To all whom it may concern:

Be it known that I, JAMES EDWARD McCALL, a citizen of the United States, and a resident of Montgomery, in the county of 5 Montgomery and State of Alabama, have made certain new and useful Improvements in Chimney-Caps, of which the following is a specification.

My invention relates to chimney caps, my 10 more particular purpose being to provide a cap having a comparatively simple form and provided with means for facilitating the escape of smoke and hot gases, while preventing the wind from blowing downwardly 15 into the chimney, and yet allowing the escape of water falling in the form of rain upon the top of the cap.

My invention further relates to the provision for arresting and returning a portion 20 of the soot, sparks, and analogous matter, so that such matter is, as far as possible, prevented from escaping from the chimney.

My invention further comprehends improved means for trapping and holding such 25 materials as are carried upward with the smoke and hot gases passing through the chimney for further combustion.

My invention also contemplates improved means for securing the chimney cap in position 30 upon the chimney.

My invention further comprehends various improvements of a mechanical nature 35 relative to the construction of chimney caps in order to improve the general efficiency of the latter.

Reference is made to the accompanying drawings forming part of this specification in which like letters indicate like parts.

Figure 1 is a perspective showing my 40 improved chimney cap ready for use, and Fig. 2 is a substantially central vertical cross section through the same.

A chimney is shown at 3, and is provided with the usual opening 4. A casing 5, which 45 in this instance is of sheet metal, has a general box-like form and rests upon the upper end of the chimney. The casing 5 is provided with base flanges 6, which are of a width commensurate with the thickness of 50 the chimney wall. Within the casing 5 are base plates 7, which are inclined; as indicated in Fig. 2, and are secured to the inner edges of the base flanges 6. The casing 5 is further provided at its upper edge with 55 a crown 8, the latter having perforations 9 extending through it. A roof 10 is con-

nected with the casing 5 and located internally thereof. This roof is provided with eaves 11 which are, in this instance, made integral with it, the roof and eaves both being made of sheet metal. Adjacent to the bottom portion of the roof are two shelves 13, each having a flange 12 secured directly to the inner surface of the casing, and by aid whereof the shelf is supported. Each 60 shelf 13 is further provided with a flange 14 extending directly downwardly.

Mounted within the casing 5, a short distance below the shelves 13 is a baffle plate 15, which is held in position by aid of bolts 16 70 extending through slots 17 in flanges 19 with which the baffle plate 15 is provided. I provide a number of straps 20, preferably of sheet metal somewhat thicker than the casing 5, and secure the casing to these 75 straps by aid of bolts 21. The straps 20 are connected directly to a belt 22, which extends completely around the chimney. In this instance the straps 20 are integral with the belt 22, but this precise construction is 80 not essential.

The operation of my device is as follows: The parts being made and assembled as above described, the casing rests directly upon the top of the chimney. Smoke and 85 gases of combustion in passing upwardly and out of the chimney encounter the baffle plate 15, and by aid of the depending flanges 18 thereof, are caused to travel slightly downward, then outward and upward around the baffle plate as indicated by 90 the arrows in Fig. 2. Any soot or masses of unburned or partially burned particles of fuel lodging upon the sloping base 7 are caused to roll back into the chimney and 95 are there subjected to further combustion. The baffle plate 15 serves, to some extent, as a trap for soot and unconsumed particles of smoke as well as floating ashes, these substances being deposited upon the top of the 100 baffle plate. The shelves 13 also serve as traps for catching floating particles which drop thereon. These particles, together with any caught by the baffle plate 15, may be readily removed at any time it may be desired to clean the chimney cap.

The holes 9 serve the double purpose of concentrating the water into definite streams, thus causing the water in falling to clear the casing 5, and conferring upon the 110 device an ornamental appearance. The wind can readily blow through the top por-

tion of the cap, but cannot blow down the chimney to any considerable extent, being obstructed by the shelves 13 and baffle plate 15 which act, to some extent, after the manner of a valve, in that they permit the smoke and gases to pass upwardly and prevent undesirable air currents from passing downwardly into the chimney.

My improved chimney cap prevents the escape of sparks from the chimney under the ordinary conditions and also when the chimney happens to catch on fire. The sparks are trapped, and effectively prevented from escaping, by the action of the depending flanges 18 of the baffle plate 15 and if in an exceptional instance any sparks succeed in passing the flanges 18 they are checked by the depending flanges 14 of the shelves 13 and drop back either into the chimney or upon the top of the baffle plate 15.

I claim:

1. A chimney cap comprising a base plate,

shelves mounted therein and adapted to support particles lodging thereon, said shelves having portions extending downwardly, a baffle plate located within said casing and below said portions of said shelves, said baffle plate being of a width greater than the distance from one of said portions to another.

2. A device of the character described comprising a casing, shelves mounted therein and extended toward each other, a baffle plate located within said casing and disposed below said shelves, said baffle plate being of a width greater than the shortest distance between adjacent portions of said shelves, and means for directing smoke and gases around said baffle plate and toward said shelves.

JAMES EDWARD McCALL.
